UNITED STATES PATENT OFFICE.

HERBERT S. JANDUS AND WAYNE E. DUNSTON, OF DETROIT, MICHIGAN, ASSIGNEES
TO THE C. G. SPRING & BUMPER COMPANY, OF DETROIT, MICHIGAN, A CORPORA-
TION OF DELAWARE.

CLAMP FOR MULTIPLE-BAR BUMPERS.

Application filed November 19, 1923. Serial No. 675,524.

To all whom it may concern:

Be it known that we, HERBERT S. JANDUS and WAYNE E. DUNSTON, citizens of the United States, residing at Detroit, in the county of Wayne and State of Michigan, have invented a certain new and useful Improvement in Clamps for Multiple-Bar Bumpers, of which the following is a full, clear, and exact description, reference being had to the accompanying drawings.

This invention relates to bumpers of the parallel multiple-bar construction, comprising at least a pair of front or impact bars and at least a single rear bar. It is the general object of the invention to provide for bumpers of this type a new and efficient center clamp for holding the central portions of the three bars in efficient assembled relation; also to provide a clamp for this purpose which is extremely simple of construction and economical of production. We accomplish the foregoing objects through the construction and arrangement of parts shown in the drawings forming a part hereof, wherein Fig. 1 represents a plan view of a bumper having our invention applied thereto; Fig. 2, a front elevation of such bumper; Fig. 3, a detail in perspective of the central portion of the bumper shown in the preceding views; Fig. 4, a central sectional elevation of such bumper, showing our clamp applied thereto; Fig. 5, a detail in perspective of one of the clamping elements; and Fig. 6, a view, similar to Fig. 4, showing a different arrangement of the clamping members and of the central portions of the bumper bars than are shown in the former view.

Describing the various parts by reference characters, 1 denotes a pair of supporting arms by which the bumper is mounted upon the adjacent portions of the vehicle side members (not shown). On the front or outer end of each arm 1 is mounted a clamp 2, said clamps being connected to the rear bar 3 of the bumper. The bumper shown herein is of the type described and claimed in McGregor Patent No. 1,372,154, issued March 22, 1921, and comprises, in addition to the rear bar 3, a pair of front or impact bars 4 connected at their ends to the ends of the bar 3 by means of bolts 5 extending through aligned eyes on the ends of said bars, the eyes 3^b on the ends of the rear bar

being positioned between the eyes at the corresponding ends of the bars 4. The central portion 3^a of the bar 3 is projected toward the central portions of the bars 4 but, in the form of our invention shown in Figs. 1-4, inclusive, is not projected a sufficient distance to bring it within the vertical plane of the bars 4, this arrangement being due to the construction and arrangement of the parts of the center clamp, which will now be described.

The central clamp comprises a plurality of identical clips, preferably made of stampings, and each being approximately C-shaped in section, one of said clips being shown in perspective in Fig. 5. Each clip comprises a vertical web 6, upper and lower bodies or flanges 6^a and 6^b, each having at its edge a flange 6^b substantially parallel with the web 6, the flanges 6^b being presented towards each other.

The flanges 6^a are provided each with a central perforation 6^c for the reception of the center clamping bolt 7, and the flanges 6^b are spaced from such perforations a sufficient distance to receive, within and between themselves and the bolt 7, the upper and lower edges of the bumper bars with which they respectively cooperate.

In the construction shown in Figs. 1-4, inclusive, the central clamping clip or member is turned 180° with respect to the upper and lower clamping clips or members, thereby to engage the central portion 3^a of the rear bar and to hold the same against the rear face of the bolt 7.

In assembling the clamping device, each member thereof will be applied to its respective bar, the members are then slid into line at the central portions of their respective bars and the stud bolt inserted into the aligned openings thereof. When the nuts 8 on the stud bolts are set up, the clamping members will spring sufficiently to insure secure engagement of the clamping members and the flanges thereof with the edge portions of their respective bars.

In Fig. 6, there is shown a modification wherein the central portion 3^a of the rear bar is deflected into the vertical plane of the central portions of the front bars. With this arrangement, all of the clamping members are applied to the plates with their flanges presented forwardly or in the same

direction, the central clamping member being turned 180° with respect to the central clamping member shown in the preceding views.

5. The clamp shown and described herein is extremely simple of construction and economical of production, but is particularly well adapted for all incidents of use and is capable of retaining the central portions of 10 the bars in proper relation to each other and without rattling.

Having thus described our invention, what we claim is:—

15 1. The combination, with a bumper comprising a pair of vertically spaced front or impact bars and an intermediate rear or auxiliary bar having its central portion projected toward the central portions of the first two bars, of a clamping device for the 20 central portions of said bars, said device comprising upper and lower C-shaped members applied to the central portions of the first two bars, respectively, and an intermediate C-shaped member applied to the 25 portion of the rear or auxiliary bar, said members having aligned apertures therethrough, and means extending through said apertures and connecting said members together.

30 2. The combination, with a bumper comprising a pair of vertically spaced front or impact bars and an intermediate rear or auxiliary bar having its central portion projected toward the central portions of 35 the first two bars, of a clamping device for the central portions of said bars, said device comprising upper, lower, and intermediate members each having an upper and a lower body and a flange projecting from each such 40 body, the flanges of each member being presented toward each other, and securing means extending through the upper and lower bodies of said members.

3. The combination, with a bumper comprising a pair of vertically spaced front or impact bars and an intermediate rear or auxiliary bar having its central portion projected toward the central portions of the first two bars, of a clamping device for the 50 central portions of said bars, said device comprising upper, lower and intermediate clamping members each having upper and lower bodies having apertures therethrough and each having a flange projecting from each such body, the flanges of each member being presented toward each other and spaced from the apertures in such bodies, a bolt extending through said apertures, and 55 means on said bolt for clamping said members together in contact with the edges of the bars which cooperate therewith.

4. The combination, with a bumper comprising a pair of vertically spaced front or impact bars and an intermediate rear or auxiliary bar having its central portion projected toward the central portions of the first two bars, of a clamping device for the central portions of said bars, said device comprising upper, lower and intermediate clamping members applied respectively to 65 the upper, lower and intermediate bars and each having upper and lower bodies having apertures therethrough with flanges projecting from said bodies, the flanges of each member being presented toward each other and being spaced from the apertures in such faces at distances corresponding to the thickness of their respective cooperating plates, the said clamping members being capable of yielding under endwise pressure, a bolt extending through the apertures in 70 said members, and a nut on said bolt for applying endwise pressure to the said members.

5. The combination, with a bumper comprising a pair of vertically spaced front or impact bars and an intermediate rear or auxiliary bar having its central portion projected toward the central portions of the first two bars, of a clamping device for the central portions of said bars, said device comprising a plurality of yieldable substantially C-shaped clamping members having vertically aligned apertures therethrough and means extending through said apertures 80 for securing said members together.

6. A clamping device for multiple-bar bumpers said device comprising a plurality of clamping members each having an intermediate web, apertured flanges projecting from said web, and a flange projecting from each of the first mentioned flanges and toward each other.

7. A clamp for multiple-bar bumpers comprising a plurality of substantially C-shaped clamping members having vertically aligned apertures therethrough, and means extending through said apertures for securing said members together in clamping engagement with their respective bumper bars.

8. A clamp for multiple-bar bumpers comprising a plurality of substantially C-shaped clamping members each adapted to engage the opposite edges of a bar, and means for securing said members together in substantially vertical alignment.

In testimony whereof, we hereunto affix our signatures.

HERBERT S. JANDUS.
WAYNE E. DUNSTON.
